UNITED STATES PATENT OFFICE.

WILLIAM EDWIN RUSSELL AND WILLIAM EARL RUSSELL, OF DANBURY, CONNECTICUT,
ASSIGNORS, BY MESNE ASSIGNMENTS, TO LOVELL-McCONNELL MANUFACTURING
COMPANY, A CORPORATION OF DELAWARE.

ALARM-HORN.

1,120,653.

Specification of Letters Patent.

Patented Dec. 8, 1914.

Application filed January 31, 1911. Serial No. 605,797.

To all whom it may concern:

Be it known that we, WILLIAM EDWIN RUSSELL and WILLIAM EARL RUSSELL, both citizens of the United States, residing in the city of Danbury, county of Fairfield, and State of Connecticut, have invented certain new and useful Improvements in Alarm-Horns; and we do declare the following to be a full, clear, and exact description of the invention, such as will enable others skilled in the art to which it appertains to make and use the same.

Our invention relates to alarm horns, and is in the nature of a modification of the improvement shown and described in our pending application Serial No. 597,493, filed December 15, 1910.

The object of the present invention is to utilize the main features of our improvement set forth in said application in connection with a suitable contact point carried by the diaphragm so that the alarm will be due solely to the vibration of the diaphragm and not to impulses communicated through perforations in the diaphragm as is the case in the instance of the improvement set forth in said application.

With these ends in view our invention consists in certain details of construction and combination of parts hereinafter fully described and then particularly pointed out in the claims which conclude this description.

In the accompanying drawing Figure 1 is an elevation partly in section illustrating our improvement—Fig. 2 an end view of the rotary head carried by the shaft of the motor—Fig. 3 an elevation of the disk or diaphragm which we prefer to employ—Fig. 4 a sectional elevation of the rotary motor head showing a modification of our improvement, and Fig. 5 an edge elevation of the diaphragm showing a modified form of contact.

Similar numbers of reference denote like parts in the several figures of the drawing. Our improvement is operated by any suitable motor, preferably actuated by electricity, to the shaft 1 of which motor is secured the rotary head 2 which is provided in its outer face with pockets 3 that are preferably inclined outwardly as shown at Fig. 1, and within these pockets are balls 4 that are confined by means of a retainer

plate 5 secured to the head 2. The balls 5 project through perforations 6 in the retainer plate the diameter of which perforations is less than the diameter of the balls. As the motor rapidly revolves the balls will be thrown outwardly by centrifugal force 60 and will bind against the sides of the inclined pockets 3.

7 is the disk or diaphragm having secured to its central portion the block 8 which latter projects from the inner face of the 65 diaphragm, and this block is recessed at 9 and within this recess is a ball 10 that is confined by means of a retainer plate 11 secured to the block. This ball 10 projects through a perforation 12 in the plate 11 and 70 the diameter of this perforation is less than the diameter of the ball. The shaft of the motor is offset and the pockets 3 are formed in the head 2 concentric with said shaft so that the balls 4 will, as the head revolves, 75 successively come in contact with the ball 10 and thereby vibrate the diaphragm 7. The balls 4, 10, are perfectly free and have a rolling contact so that there is comparatively little friction to retard the speed of 80 the motor. If desired, the balls 4 may be backed by coil springs as shown at 13 in the instance of one of the balls at Fig. 1, so that there will be initially a good contact against the ball 10 while the motor is getting up speed but we do not wish to be limited in this respect since springs of this sort are not at all necessary. In case coil springs were used to back the balls 4 the pockets 3 could be parallel with the shaft 1, 90 and not flared. While we prefer to utilize pockets providing spaces behind the balls 4 so that the latter may yield more or less when contacting against the ball 10, we do not wish to be limited in this respect since 95 shallow circular pockets 14, as shown at Fig. 4, may be employed against the bottoms of which pockets the balls always rest, but the balls 4 in all instances are perfectly free to revolve in any direction. Instead of 100 a rolling contact on the diaphragm 7 we can employ a contact 15 rigidly secured to the diaphragm, such as is shown at Fig. 5 but we prefer the construction shown at Fig. 1 since it gives the best results.

16 is the motor casing to which is secured in any suitable manner the base 17 of any approved horn or resonator 18, the dia-

phragm being confined in position at its outer edge between said base and casing.

Having thus described our invention what we claim as new and desire to secure by Letters Patent is:—

5. 1. An alarm horn, comprising a horn or resonator, a diaphragm carrying on its inner face a rolling contact, and a rotary head carrying free rotating balls adapted to successively engage said contact.
10. 2. An alarm horn, comprising a horn or resonator, a diaphragm, a rolling contact carried by the inner face of said diaphragm, a rotary head, and guided rotary balls carried thereby adapted to be successively brought into forcible engagement with said contact.
15. 3. An alarm horn, comprising a horn or resonator, a diaphragm, a contact carried by the inner face of said diaphragm, a rotary head having recesses, balls freely contained within said recesses and adapted to successively engage said contact as the head revolves.
20. 4. An alarm horn, comprising a horn or resonator, a diaphragm carrying on its inner face a rolling contact, and a rotary head carrying rolling contact members adapted to successively engage said contact.
25. 5. In an alarm signal of the character described, a diaphragm, a plurality of strikers, a rotatable carrier for said strikers, an intermediate blow transmitter arranged between said strikers and said diaphragm, said strikers and said blow transmitter being hardened steel balls free to rotate about their own axes.
30. 6. In an alarm signal of the character described, a diaphragm, a plurality of strikers, a rotatable carrier for said strikers, an intermediate blow transmitter arranged between said strikers and said diaphragm, said strikers and said blow transmitter being hardened and free to rotate about their own axes respectively.
35. 7. An alarm horn comprising a horn or resonator, a diaphragm carrying on its inner face a rolling contact, a rotary head, and rolling contact members carried thereby and guided therein and adapted to successively engage said contact.
40. 8. An alarm horn including a diaphragm having a socket member secured thereto adjacent to the center, a rotatable ball disposed within said socket, a pair of diaphragm 55 clamping members, a resonator carried by one of said members, and a high speed electric motor carried by the other of said members, and having its shaft substantially at right-angles to the plane of said diaphragm 60 and eccentric in respect to a line normal to said diaphragm and extending through said ball and a rotor carried by said motor shaft and presenting a series of rolling contact members adapted for successive engagement 65 with said ball to vibrate said diaphragm.
45. 9. An alarm horn including a diaphragm having a wear piece adjacent to the center thereof, a frame member having its peripheral portion held rigid in respect to the peripheral portion of the diaphragm, and a high speed electric motor secured to said frame member, and having its axis substantially at right-angles to said frame member and eccentric in respect thereto, and a rotor 70 between said frame member and said diaphragm, and having recesses in the face thereof, and carried by said shaft, and having a series of rotatable contacts freely contained within said recesses adapted for successive engagement with said wear piece.
50. 10. An alarm horn including a diaphragm having a rotatable wear piece adjacent to the center thereof, a frame member having its peripheral portion held rigid in respect 75 to the peripheral portion of the diaphragm, and a high speed electric motor secured to said frame member, and having its axis substantially at right-angles to said frame member and eccentric in respect thereto, and a rotor 80 between said frame member and said diaphragm, and having recesses in the face thereof, and carried by said shaft, and having a series of rotatable contacts adapted for successive engagement with said wear piece.
55. 11. In testimony whereof we affix our signatures in presence of two witnesses.

WILLIAM EDWIN RUSSELL.
WILLIAM EARL RUSSELL.
